Primary Examiner — Patricia Palasik(74) *Attorney, Agent, or Firm* — Norris McLaughlin & Marcus PA(57) **CLAIM**

The ornamental design for an ultrasonic welding sheath, as shown and described.

DESCRIPTION

FIG. 1 is a perspective view showing the front and a side of the ultrasonic welding sheath;

FIG. 2 is an elevation view of a first side of the ultrasonic welding sheath;

FIG. 3 is an elevation view of a second side of the ultrasonic welding sheath;

FIG. 4 is a plan view of the top of the ultrasonic welding sheath;

FIG. 5 is a plan view of the bottom of the ultrasonic welding sheath;

FIG. 6 is an elevation view of one end of the ultrasonic welding sheath,

FIG. 7 is an elevation view of another end of the ultrasonic welding sheath; and,

FIG. 8 is an elevation view of the second side of the ultrasonic welding sheath mounted upon an ultrasonic welding device. The broken lines in the drawings depict unclaimed environmental subject matter.
